UNITED STATES PATENT OFFICE

HARVEY FELDMEIER, OF LITTLE FALLS, NEW YORK, ASSIGNOR, BY MESNE ASSIGNMENTS, TO CHERRY-BURRELL CORPORATION, OF WILMINGTON, DELAWARE, A CORPORATION OF DELAWARE

TANK

Application filed September 23, 1926. Serial No. 137,221.

This invention relates to tanks and particularly to the type designed for the transportation of liquids such as milk.

With the growth of good roads and the development of automobile trucks, there has been a demand for an efficient motor tank truck for transporting liquids such as milk in bulk, and when the liquids are perishable, such as milk, the tank should be insulated so as to prevent temperature changes in the contents while being transported. Heretofore glass lined tanks have been employed for this purpose, but such tanks have been very heavy and fragile.

An object of this invention is to provide an improved tank for transporting liquids, such as milk, in bulk, which will be exceptionally light in weight for a given capacity; which will not be broken or injured by vibrations or shocks to which it is subjected during transportation; which will present to the liquid a surface of material unaffected by the liquid being transported; and which will be relatively strong, simple, durable, efficient, practical and inexpensive.

A further object of the invention is to provide an improved method of making tanks for the transportation of liquids which will be relatively simple and inexpensive and which will provide a tank exceptionally light in weight, and relatively strong and durable.

Various other objects and advantages will be apparent from the following description of an embodiment of the invention, and the novel features will be particularly pointed out hereinafter in connection with the appended claims.

In the accompanying drawings:—

Fig. 1 is a side elevation of a tank constructed in accordance with this invention;

Fig. 2 is a transverse, sectional elevation of the same;

Fig. 3 is a transverse, sectional elevation of a portion of the same, but on a somewhat larger scale;

Fig. 4 is a transverse sectional elevation of another part of the tank;

Fig. 5 is a longitudinal, sectional elevation through the manhole section of the tank; and

Fig. 6 is a fragmentary, longitudinal sec-

tion on an enlarged scale, through the walls of the tank.

In the illustrated embodiment of the invention, I provide an approximately cylindrical container 1 of relatively thin sheet material such as sheet metal, and when the tank is to be used for the transportation of milk, cream or the like, the container 1 may be formed of nickel sheets preferably welded together. This container 1 is provided in its cylindrical wall with a manhole 2, in which is fitted a neck or ring 3 having a peripheral flange 4 extending slightly along and overlapping with the sheet material of the container 1 adjoining the opening 2, and this flange is secured to the container 1 in any suitable manner, such as by rivets 5 and also and preferably, by welding the edges of the flange to the container.

The neck or ring 3 extends outwardly for some distance, and then is provided with an inwardly extending seat or shoulder 6 which is parallel to the flange 4 but of smaller diameter. The neck 3 extends outwardly for a suitable distance beyond the seat 6. A cylindrical jacket shell 7 surrounds the cylindrical wall of the container, and is provided with an opening concentric with the opening 2 of the container, and through which the neck or ring 3 extends, so that the shell wall fits upon the seat 6 of the neck or ring, in spaced relation to the container. Suitable screws 9 pass through the ring 8, and are threaded into the neck or ring 3, so as to clamp the shell 7 firmly to the seat 6. Suitable gasket rings 10 may be disposed between the seat 6 and the shell 7 and between the shell 7 and the clamping ring 8.

The container is enclosed in a layer of heat insulating material 11, such as sheet cork and the thickness of this layer may be approximately that of the distance between the container and the seat 6, so that the insulating layer will fill the space between the shell 7 and the container. The sheet insulating material for the cylindrical portion of the container is preferably provided in the form of strips of sheet cork which are disposed edge-wise to one another and extending in directions endwise of the container, so as to corre-

- spond somewhat to the staves of a tub or barrel in the arrangement about the container. The abutting edges of these strips of insulating material may be bevelled slightly so as to fit closely together like the staves of a barrel. The shell 7 is slit endwise at one point of its periphery, and the edge portions 12 and 13, see Fig. 3, along the slit are preferably overlapped with one another.
- 5 10 Adjacent the slit, suitable angular bars or strips 14 are secured to the shell 7, with the bars extending parallel to the slit. Suitable connectors, such as bolts 15, connect the strips 14 and are used to draw the edges of the shell 7 abutting the slit into more or less overlapping relation to one another, so as to contract the shell 7 tightly around the container and insulating layer. The strips of insulating material, however, are preferably confined to the container 1 before the application of the shell 7 thereto, by suitable straps or wires 16 which surround the container and layer, as shown particularly in Fig. 3. When the shell 7 is contracted, it will draw the insulating staves or strips tightly together and press them firmly against the container 1, so as to stiffen and reinforce the same, the shell 7 acting somewhat as the hoops of a barrel, except that it is a substantially continuous enclosing jacket.
- 15 20 After the shell 7 has been contracted upon the container and its insulating layer, heads 17 for the shell 7 are placed in the ends of the shell and against the ends of the container 1, with the insulating material 11 interposed between the ends of the container and the heads 17, as shown in Fig. 1. The heads 17 are provided with peripheral flanges which extend peripherally along the ends of the shell 7, and these flanges may be secured to the shell 7 by rivets or bolts 18. The heads 17 are of a diameter slightly less than the combined diameter of the container 1, and its insulating layer, and are secured to the shell 7 after the latter has been contracted upon the container.
- 25 30 Therefore, the container will be peripherally reinforced tightly throughout, and the heads fit snugly against the ends of the container and layers of the insulating material so as to prevent bulging of the ends of the container. The heads 17 and the shell 7 together constitute what may be termed a contractible jacket for enclosing the container and insulating material. Bolts 18 are preferred as the means for fastening the heads 17 to the shell 7, because they enable the heads 17 to be removed more easily in case repairs are necessary.
- 35 40 45 The jacketed container may be secured to a platform or frame 19 in any suitable manner, such as by straps 20 which extend over the tank and have adjustable connections to arms 21 which extend from the platform or frame 19. The ring 8 which confines the
- shell 7 to the manhole neck or ring 3 may be provided with a plurality of upwardly extending bearing lugs 22, to which rods 23 are hinged, as shown in Fig. 4. The rods 23 may be swung upwardly, so as to enter slots or notches in the edges of a cover 24. The latter is hinged by a pin 25 to hinge ears 26 on the neck 3, so as to swing into and out of closed position over the open end of the manhole ring or neck 3. Nuts 27 may be threaded upon the projecting ends of the rods 23, so that when the rods are swung into the peripheral notches of the cover, the nuts may be tightened to clamp the cover firmly across the open end of the ring 3. A suitable compressible gasket 24^a, preferably a flat rubber ring, may be disposed between the cover and the open end of the manhole ring or neck.
- 50 55 60 65 70 75 80 85 90 95 100 105 110 115 120 125 130 To permit a firm closure, the connection between the pivot pin 25 and cover is capable of a limited vertical lost motion, so that the cover may adjust itself uniformly and firmly to the manhole neck 3. The cover may have an open boss 28 which is closed by a removable ventilating cap 29, as shown in Fig. 5. The container 1 may also have a valve controlled drain pipe 30 extending from one end and adjacent its lower edge, this valve controlled pipe 30 extending through the insulating layer and one end head 17 of the jacket.
- 125 130 I have found that the lining or container 1 of the tank may be made of pure nickel sheets of approximately .065 to .078 inch thick and the seams welded, and that the insulating layer may be made of cork sheets approximately two inches in thickness. The stave strips of insulating material may be four or five inches wide, for example. The outer enclosing jacket may be of sheet steel with the seams welded or riveted, as desired. The glass lined steel tanks heretofore used for this purpose were from one-fourth to three-eighths inch thick, with the two-inch insulating layer and enclosing sheet steel jacket. Such a tank was very heavy and cumbersome. By using a lining or container having walls of one about one-sixteenth inch instead of one-fourth or three-eighths inch, as heretofore, I have made a saving in weight of the tank of from eight hundred to one thousand pounds on single tanks of eight hundred to one thousand gallons capacity. This saving in weight is very important, both as to wear and tear on the truck, and also on account of the fact that the taxes and license charges on these trucks are based upon the total weight of the truck in most of the States. The thin lining of nickel sheets which I employ are properly stiffened and supported by the insulation and the enclosing jacket which is contracted to grip the lining tightly and force it firmly and uniformly against the inner shell or container 1. While there is less possible contraction of the shell 7 at its ends, it has been found that there is sufficient con-

traction in the center and into proximity to the ends, to obtain the desired results.

It will be obvious that various changes in the details which have been herein described and illustrated in order to explain the invention may be made by those skilled in the art within the principle and scope of the invention as expressed in the appended claims.

I claim as my invention:—

1. A tank for transporting liquids under conditions which create torsional stresses in the walls thereof which comprises a container of relatively thin sheet metal, a layer of heat insulating material entirely surrounding said container, and a stress-resisting jacket enclosing said layer and container, and means to draw and hold said jacket in uniformly close contact with said layer.
2. A tank for transporting liquids under conditions which create torsional stresses in the walls thereof which comprises an approximately cylindrical container of relatively thin sheet material, a layer of heat insulating material covering said container, including its entire underside thereof, an approximately cylindrical stress-resisting jacket enclosing the insulating layer and container including the bottom of said container and having its cylindrical wall slit lengthwise, with the edges abutting the slit overlapping one another, and means for drawing the overlapping edges into more or less overlapping relation so as to compress and hold the insulating layer in uniformly close contact with the cylindrical container wall to stiffen the same.
3. A tank for transporting liquids under conditions which create torsional stresses in the walls thereof which comprises an approximately cylindrical container of relatively thin sheet material, a layer of insulating material covering the cylindrical section and end walls of said container, an approximately cylindrical stress-resisting jacket entirely encircling the insulating layer and container and approximately co-extensive in length with said container and insulating material, said jacket being slit lengthwise with the edges of the slit overlapping one another, means adjacent the slit for drawing the edges adjoining the slit into more or less overlapping engagement with one another, so as to draw and hold the insulating layer uniformly in close contact with the container, and end walls for said jacket secured to the contracted ends of said jacket.
4. A tank for transporting liquids which comprises a horizontally disposed container of relatively thin material having an opening in the top wall, a manhole ring secured in said opening and extending outwardly therefrom, said ring having a peripheral flange portion for attachment to a face of the container wall and having on the outwardly projecting portion an inwardly extending annular seat of smaller diameter but parallel to

said flange, a jacket of sheet metal enclosing the container and resting upon said seat, means for securing the jacket to said seat, and sheet insulating material compressed between said jacket and container and abutting edgewise around said ring.

5. The method of producing tanks for transporting liquids which comprises enclosing an approximately cylindrical container of relatively thin material with a layer of heat insulating material, peripherally encircling said container and layer with an approximately cylindrical shell slit lengthwise, drawing said shell tightly about the insulating layer and container to press the insulating layer firmly against the container wall to stiffen the same, and after the shell has been contracted securing to the ends of said shell heads of a diameter slightly less than the combined diameter of the container and insulating layer.
